UNITED STATES PATENT OFFICE.

HENRY D. MEARS, OF NEW YORK, N. Y.

IMPROVEMENT IN SEALING BOXES, &c.

Specification forming part of Letters Patent No. 95,368, dated September 28, 1869.

To all whom it may concern:

Be it known that I, HENRY D. MEARS, of the city, county, and State of New York, have invented certain new and useful Improvements in Cording and Sealing Boxes, Bales, Packages, &c.; and I do hereby declare the following to be a full, clear, and exact description of the same, reference being had to the accompanying drawing, making a part of this specification, and which represents in perspective a box corded and sealed after my general plan, the cords in red ink showing the peculiar feature of my invention, that in black not being herein claimed.

I am aware that boxes, bales, and packages have been corded with wire. This I do not claim. I am also aware that a metallic seal has been used in various ways. To this I lay no claim in this application. I am also aware that boxes, bales, &c., have been corded with a hempen rope and sealed with some kind of a seal. This I lay no claim to. Neither of the above things involve what I aim at, nor does it accomplish the purpose I have in view, nor the application of this mode of cording and sealing to articles transported under bond, as it were, not to be opened.

My invention consists in cording and sealing boxes and other similar transportable articles with metallic cords or wires passing through said article, and sealing the ends of the thus binding metallic cords or wires by a metallic seal, so that the box, bale, package, or other article cannot be opened without breaking the cord or wire or seal, or both, and thus exposing the fact.

To enable others skilled in the art to make and use my invention, I will proceed to describe the same with reference to the drawing.

A represents a box to which my mode of cording and sealing is applied (shown in red ink) in two different ways, so as to fully illustrate the plan. The wire cord d is passed

through the top and sides, (or the top and ends, or both,) at the corners, as seen at e e, and the ends, when brought together, are looped, knotted, or twisted, as shown at f, and the ends beyond this sealed with a metallic seal, g, marked, stamped, or pressed in characters or otherwise to show its character, as explained above. This cordage could not be removed without breaking it, its seal, or the wood or material it thus passes through.

At h is shown another plan, much like that just above described, though more simple, and is more applicable to such boxes, bales, or packages as have their tops hinged at one side. The wire i in this case is simply passed through holes j j, made through the corner, or so as to unite the lid with the body of the article, and the seal k applied immediately to the ends of the wire. The ends may, however, be looped or twisted together and then sealed, and the seal in this case, as in the others, may be used to detect any violence in opening the article sealed; or it may designate value, destination, import duty, tax, revenue, or the want of them. The wire used may be of some corrosive resisting material, and when made of two or more strands twisted together form such an exterior surface as will firmly hold the soft-metal seal when tightly pressed against or around it. Copper or galvanized wire are the best for this purpose.

Having thus fully described my invention, what I claim therein as new, and desire to secure by Letters Patent, is—

Cording and sealing boxes and other similar articles to be transported by means of a metal cord or wire passing through said article, and securing the ends thereof by a metallic seal, as and for the purpose herein described and represented.

HENRY D. MEARS.
